UNITED STATES PATENT OFFICE.

WILLIS EZRA JOHNSON, OF NEWNAN, GEORGIA.

DESIGN FOR A CASING FOR WEIGHING-MACHINES.

45,046.

Specification for Design.

Patented Dec. 16, 1913.

Application filed September 24, 1913. Serial No. 791,654. Term of patent 3½ years.

To all whom it may concern:

Be it known that I, WILLIS EZRA JOHNSON, a citizen of the United States, residing at Newnan, in the county of Coweta and State of Georgia, have invented a new, original, and ornamental Design for a Casing for Weighing-Machines, of which the following is a specification, reference being had to the accompanying drawing, forming part thereof.

Figure 1 is a front elevation of a casing for weighing machines showing my new design. Fig. 2 is a side elevation.

I claim:

The ornamental design for a casing for weighing machines as shown.

WILLIS EZRA JOHNSON.

Witnesses:

F. WILLIAMS,

M. G. THUMM.
